UNITED STATES PATENT OFFICE.

JOHN W. LONGWORTH, OF GRAND RAPIDS, MICHIGAN, ASSIGNOR TO ABEN E. JOHNSON,
OF HASTINGS, MICHIGAN.

BURGLAR ALARM.

Application filed December 8, 1921. Serial No. 520,795.

To all whom it may concern:

Be it known that I, JOHN W. LONGWORTH, a citizen of the United States, residing at Grand Rapids, county of Kent, State of Michigan, have invented certain new and useful Improvements in Burglar Alarms, of which the following is a specification.

This invention relates to improvements in burglar alarms.

10 The main objects of the invention are:

First, to provide an improved burglar alarm which may be placed in operative relation to a door merely by suspending or hanging upon a door knob, the alarm being 15 actuated by a turning movement of the knob.

Second, to provide an improved burglar alarm which is very compact, so that it may be easily transported, is quickly set and is positive in operation.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated 30 in the accompanying drawing, forming a part of this application, in which:

Fig. I is a front elevation of my improved burglar alarm applied to a door, a fragment only of the door being shown.

35 Fig. II is a vertical section of the alarm on a line corresponding to line 2—2 of Figs. I, II and IV, parts being shown in full lines for convenience in illustration.

Fig. III is a vertical section on a line 40 corresponding to line 3—3 of Figs. II and V.

Fig. IV is a front view with parts broken away to show structural details.

Fig. V is a vertical section on a line 45 corresponding to line 5—5 of Fig. III.

In the drawing similar reference characters refer to similar parts throughout the several views and the sectional views are taken looking in the direction of the little 50 arrows at the ends of the section lines.

Referring to the drawing, 1 represents a door. 2 a door knob, and 3 a key. These parts are shown conventionally.

55 My improved burglar alarm comprises a casing or housing 4 open at the rear to re-

ceive the knob 2 and the key of a door. An alarm, designated generally by the numeral 5, is mounted on the front wall of the casing. This alarm is driven from a spring 6 wound by means of the front portion 7 of the casing which is mounted on the shaft 8. This shaft drives a train of gears, designated generally by the numeral 9, the train of gears driving the ratchet wheel 10 acting upon the pawl 11 carrying the striker 12. The structural details of these parts are no part of this invention.

The alarm is controlled by the control member 13 pivoted at 14 and having a lug 15 projecting under the arm of the striker 12 so that when this control member is in locking position the pawl 11 is locked in engagement with the ratchet 10, thereby locking the alarm, and when the control member is in releasing position this pawl 11 is freed so that the alarm is sounded.

An actuating roller 16 is mounted in the upper part of the housing to coact with the roller 17 in supporting the housing upon the knob, that is, these rollers rest upon the knob, as is indicated by dotted lines in Fig. IV. The roller 16 is provided with a dog 18 adapted to swing under a lug 19 on the control member and support the control member in its locked position. When the roller 16 is actuated, as by the turning of the knob, the dog passes out from under this lug 19 allowing the alarm to sound.

To set the roller and the control member and also to lock them in set position while the alarm is being handled, as in placing upon the knob, I provide a setting and locking slide 20 mounted in slideways 21 on the side of the housing, so that the slide is supported at the side of the roller 16. This 90 slide is provided with a cam slot 22 coacting with a pin 23 on the roller, so that when the slide is moved rearwardly the roller is positioned to lock the control member. The slide is also provided with a cam slot 24 coacting with the arm 25 on the control member to swing it to locking position or into coacting relation with the dog 18 on the roller.

The slide has a finger-piece 26 projecting 105 through a slot 27 in the side of the casing so that by moving this slide rearwardly the roller and the control member are set and are locked in a set position until the slide is again moved forwardly. This is 110

of material advantage in placing the alarm upon a knob as it may be placed upon the knob while locked in set position and then released. A very slight turning of the knob 5 releases the alarm.

A spring 28 is preferably provided in the bottom of the housing to engage with the key 3.

My improved alarm is compact so that 10 it may be conveniently carried about and is quickly applied to and removed from the knob as desired.

I have illustrated and described my improvements in an embodiment which I consider very practical. I have not attempted 15 to illustrate various modifications or adaptations which I contemplate, as I believe the disclosure made will enable those skilled in the art to which my invention relates to 20 embody or adapt the same as may be desired.

Having thus described my invention, what I claim as new and desire to secure by Letters Patent, is:

25 1. In a burglar alarm, the combination of a housing open at the rear to receive a door-knob, an alarm, a pivoted alarm control member, means for supporting said housing upon a door knob comprising a roller mounted in said housing to be engaged with a knob, a dog on said roller coacting with said alarm control member for holding it in alarm locking position, a setting and locking slide mounted in said housing at the side of said 30 roller and having a pair of cam slots, a pin on said roller coacting with one of said cam slots, and an arm on said alarm control member coacting with the other of said cam slots so that the roller and the 35 alarm control member are set and retained in set position when the slide is moved to locking position.

40 2. In a burglar alarm, the combination of a housing adapted to receive a door knob, an alarm, an alarm control member, means for supporting said housing upon a door knob comprising a roller mounted in said housing to be engaged with a knob, a dog on said roller coacting with said alarm control member for holding said member in 45 alarm locking position, said dog being disengaged by the rotative movement of said roller, a setting and locking member having cam slots therein, a pin on said roller coacting with one of said cam slots, and an 50 arm on said alarm control member coacting with the other of said cam slots so that the roller and the alarm control member are set and retained in set position.

55 60 3. In a burglar alarm, the combination with a housing adapted to receive a door knob, an alarm, a pair of rollers arranged in said housing to rest upon a door knob, means for controlling the alarm including 65 one of said rollers adapted to release the

alarm on the rotative movement of the roller, means for holding said roller in set position, and a spring mounted in said housing to engage the key of a door lock when the rollers are engaged with the knob of 70 a lock.

4. In a burglar alarm, the combination with a housing adapted to receive a door knob, an alarm, a pair of rollers arranged in said housing to rest upon a door knob, means 75 for controlling the alarm including one of said rollers adapted to release the alarm on the rotative movement of the roller, and means for holding said roller in set position.

5. In a burglar alarm, the combination 80 with a housing adapted to receive a door knob, an alarm, a pair of rollers arranged in said housing to rest upon a door knob, means for controlling the alarm including one of said rollers adapted to release the alarm 85 on the rotative movement of the roller, and a spring mounted in said housing to engage the key of a door lock when the rollers are engaged with the knob of a lock.

6. In a burglar alarm, the combination 90 with a housing adapted to receive a door knob, an alarm, a pair of rollers arranged in said housing to rest upon a door knob, means for controlling the alarm including one of said rollers adapted to release the alarm on 95 the rotative movement of the roller.

7. In a burglar alarm, the combination of a housing, an alarm carried thereby, means for supporting said housing upon a door knob comprising an actuating roller, an 100 alarm control member, a dog on said roller coacting with said alarm control member for holding it in alarm locking position, and a setting and locking member adapted to set the alarm control member and bring the 105 dog on the roller into coacting relation thereto.

8. In a burglar alarm, the combination of a housing, an alarm carried thereby, means for supporting said housing upon a door 110 knob comprising an actuating roller, an alarm control member, and a dog on said roller coacting with said alarm control member for holding it in alarm locking position.

9. In a burglar alarm, the combination 115 with a housing, an alarm, an alarm control member, means for holding said alarm control member in locking position comprising a roller adapted to be engaged with a knob, and means for locking said roller in set 120 position.

10. In a burglar alarm, the combination with a housing, an alarm, an alarm control member and means for holding said alarm control member in locking position comprising 125 a roller adapted to be engaged with a knob.

In witness whereof, I have hereunto set my hand and seal.

JNO. W. LONGWORTH. [L.S.]
